**AWNNG STRUCTURE AND METHOD OF
MAKING SAME**

Nicholas L. Etten, Cedar Falls, Iowa, assignor to Chamberlain Corporation, Waterloo, Iowa, a corporation of Iowa

Application February 17, 1951, Serial No. 211,547

3 Claims. (Cl. 20—57.5)

This invention relates to improvements in an awning structure and method of making the same, and more particularly to a stationary awning for disposition over windows, doorways, etc. of homes, stores, and similar buildings to both perform the general sun shading function of an awning and at the same time by virtue of its decorative character enhance the exterior appearance of the entire building, although the invention may have other uses and purposes as will be apparent to one skilled in the art.

In the past, many and various types of awnings, both ventilative and non-ventilative in character, and made of metal or similar material colored as desired, have been developed and used. In many cases, such structures have been objectionable insofar as expense of manufacture is concerned, and in view of the numerous sizes that had to be made to accommodate all the various size windows and other openings over which an awning may be disposed. In every instance of which I am aware, a completed awning, especially a metallic one, cannot be adjusted as to width after once being completed. Therefore, if a window were an inch or two narrower or broader than the closest size awning obtainable, special awnings would have to be made but that is in most instances prohibitively expensive. In other instances, awnings of this character heretofore known did not provide sufficient ventilation, did not provide adequate drainage, and were not always as pleasing in appearance as may be desired.

With the foregoing in mind, it is an important object of the instant invention to provide a stationary awning that is extremely economical to manufacture and which embodies slats interlocked with each other and extending longitudinally of the canopy of the awning.

Another feature of the invention resides in the provision of a ventilation type fixed awning with the slats so constructed as to form drain channels for the ready removal of moisture from the awning.

Another object of the instant invention is to provide an awning embodying a plurality of slats extending longitudinally of the canopy of the awning, but which slats are inclined laterally to the horizontal.

Another object of the invention resides in the provision of an awning of the character herein set forth embodying slats extending longitudinally of the canopy of the awning and in which the center portion of the canopy is peaked, sloping laterally both ways from the median line of the canopy.

A further feature of the invention resides in the provision of an awning embodying separated slats extending longitudinally of the canopy of the awning, the slats providing adequate ventilation through the canopy of the awning, and at the same time being loosely interlocked to provide adequate drainage, and wherein the canopy has an integrally formed vertically hanging skirt across the front thereof.

Another desideratum of the invention resides in the provision of a fixed ventilation type awning that may be varied in width at the time of manufacture to a rela-

2

tively great extent and to very fine dimensions, and still be made economically in mass production. Thus, awnings of substantially any width may be provided in mass production with but a negligible addition in cost, even if specially ordered.

It is also a feature of the invention to provide an awning in which the widths of the canopy may be varied during manufacture, with no change in the slats of the canopy or the end panels of the awning being necessary.

10 It is also a feature of this invention to provide a new and novel method of making an awning of the character set forth herein.

While some of the more salient features, characteristics and advantages of the instant invention have been above pointed out, others will become apparent from the following disclosures, taken in conjunction with the accompanying drawings, in which—

Figure 1 is a fragmentary pictorial illustration of an awning embodying principles of the instant invention shown mounted in operating position over a window;

Figure 2 is an enlarged fragmentary front elevational view of the awning structure alone, with parts broken away to show interior construction;

Figure 3 is a vertical sectional view through the awning and its mounting taken substantially as indicated by the line III—III of Fig. 2, looking in the direction of the arrows;

Figure 4 is a fragmentary enlarged bottom plan view of the underside of an end panel and the underside of the canopy, taken substantially from the left-hand side of Fig. 1, with the central portion of the canopy eliminated for purposes of clarity; and

Figure 5 is an enlarged fragmentary vertical sectional view through the canopy portion of the awning taken substantially as indicated by the line V—V of Fig. 2.

As shown on the drawings:

With reference to Fig. 1 it will be seen that the illustrated embodiment of the instant invention is shown associated with a building 1 and attached to the sash frame 2 of a window. The upper portion of the awning is preferably suspended from a pair of spaced hooks 3—3, Figs. 2 and 3, which are screwed or equivalently mounted on the sash frame 2.

With reference again to Fig. 1, it will be seen that the awning itself includes a canopy generally indicated by numeral 4, a pair of like end panels generally indicated by numeral 5, and a water shed generally indicated by numeral 6. The entire awning structure, save for rivets, bolts, and the like, is preferably made of stamped metal, aluminum being highly satisfactory for this purpose, although sheet metal of substantially any kind may also be used. The outer and inner surfaces of the metal are preferably covered with any suitable paint or enamel in any desired colors or color schemes.

With reference to Figs. 3, 4 and 5, it will be seen that each end frame 5 is of generally triangular configuration. Each end frame embodies a horizontal reinforcing rail or batten, generally indicated by numeral 7, and of angular shape, having an inwardly extending lateral flange 8 and a depending flange 9. The depending flange 9 is slotted at intervals as indicated at 10 to form spaced slat holding brackets or teeth 11 which, as seen best in Fig. 4, are so bent as to assume an inclined or angular position relatively to the depending flange 9. One end of each bracket 11 is substantially flush with the depending flange 9 of the batten, while the other end is spaced outwardly therefrom. As seen best in Fig. 3, the inner end of the horizontal flange 8 is turned downwardly as at 12 and bolted or equivalently secured to the sash frame 2 as indicated at 13 when the awning is mounted.

Each end frame also includes a similarly formed reinforcing rail or batten 14 at the upper portion thereof,

but which is disposed at an angle to the lower batten 7 to provide the hypotenuse for the generally triangular configuration of the end panel. The batten 14 is of substantially the same construction as the batten 7 just above described. The inner end portion of the upper flange of the batten 14 is extended as indicated at 15 in Fig. 5 and is also provided with an aperture to engage over the aforesaid hook 3 mounted on the sash frame 2.

Extending vertically and secured to each of the battens 7 and 14 is a plurality of slats 16, certain of which extend slightly below others, preferably in an alternative manner as seen clearly in Figs. 1 and 3 for decorative purposes.

As seen clearly in Fig. 4, each of these slats is of substantially a flattened Z shape in cross section and embodies a flat central portion 17 having an inwardly extending flange 18 along one side edge thereof, and a similar outwardly turned flange 19 along the opposite side edge. The central portion 17 of each flange is riveted or equivalently secured to each of the battens 7 and 14 as indicated at 20. These slats are so arranged that the inwardly turned flange 18 of one slat overlaps and engages the outwardly turned flange 19 of the next adjacent slat, so that there is no space between them and consequently no opening through either end frame. Should ventilation through an end frame be desired, the slats may be mounted with the same interlocking effect, but with the adjacent flanges 18 and 19 spaced slightly apart to provide a tortuous passageway between slats for air, although in practically every installation there is no need whatever for ventilation through the end panels.

As is evident from the showing in Fig. 3, the upper ends of the slats 16 are cut off slantwise in keeping with the slope of the batten 14 and terminate substantially flush with the upper surface of this batten.

The awning canopy includes a pair of spaced transversely extending battens 21-21 of identical construction which are bolted or equivalently secured to the lateral flanges of the end frame battens 14-14 as indicated at 22 in Fig. 5. This canopy also includes a batten 23 extending transversely across the skirt portion of the canopy, this batten being substantially identical in construction with the above described end frame batten 7 with the exception that its slat supporting brackets are bent in opposite directions on either side of its center as will more fully later appear. The batten 23 is bolted or equivalently secured to the lower battens 7-7 of the end panels as indicated at 24 in Figs. 2 and 3.

With reference now to Fig. 4 it will be seen that the slat supporting brackets of the batten 23 slope inwardly toward the left-hand end panel as one faces the awning from the outside for half the width of the canopy as indicated at 25, and slope inwardly in the opposite direction toward the right-hand end panel on the other side of the center line as indicated at 26. The same is true with the slat supporting brackets 27 of the battens 21-21.

At each end thereof, each of the battens 21-21 and the batten 23 is provided with a shorter slat supporting bracket 28 to permit room for the end connections of all these battens with those on the respective end panels.

The awning canopy includes a plurality of slats 29 extending longitudinally of the canopy, and these slats are of the same construction as the slats 16 above described, with one exception, namely that the forward portions thereof are split in the flanges as indicated at 30 in Fig. 3 so that the slats may be bent downwardly to form the skirt extending across the front of the canopy. In fact, a small triangular notch is made in each vertical flange of each slat, and when the bend is accomplished, the side edges of the notches abut each other. Now with reference again to Fig. 4, it will be noted that the two slats 29 as the very center of the canopy have respective downwardly turned flanges in abutment as indicated at 31. In other words, the slats on one half the canopy are reversed in position to those on the other side in that on

both sides the downwardly extending flange of each slat is towards the center of the awning. This leaves a double slat combination of peaked formation to enhance the appearance of the canopy as a whole. These slats 29 are, of course, riveted to the respective batten brackets as indicated at 32 in the same manner as above described in connection with the end frames or panels.

It will be noted from the showing in Figs. 4 and 5 that at each side edge of the canopy, a slat 33 is provided which has both flanges downwardly turned. Thus the innermost flange may be in an interlocking relation with the upwardly turned flange of the adjacent slat, while the outer flange forms a screen as at 34 to conceal the upper marginal portion of the adjacent end panel and thus enhance the appearance of the awning as a whole.

At the top of the awning, to prevent any leakage between the awning and the window it covers, is a water shed 6. This water shed embodies an upstanding flange 35 turned inwardly at the top as at 36 to contact the sash frame above the hooks 3-3 as best seen in Fig. 3. The water shed may be attached by means of a screw 37 or the equivalent which preferably passes through a suitable aperture in the adjacent hook 3 and into the sash frame behind the hook. The water shed also includes a sloping forward panel 38, the end portions of which are bent obliquely as indicated at 39 to intimately overlie the sloping portion of the end slats 33-33 of the canopy.

In mounting the awning in position, it is a simple expedient to first attach the hooks 3-3 to the sash frame in required locations. Then the entire awning including the end panels and the canopy is hocked over the hooks 3-3, and the screws 13 in the lower of the end frame battens 7-7 secured in the sash frame. After that it is a simple expedient to put the water shed in position. Thus it will be seen that one man can easily mount the entire awning in place.

The instant awning lends itself to the economical mass production manufacture of awnings in almost any desired width. The transverse battens 21-21, and 23 are simple stampings, as is the water shed 6. These stampings may be lengthened or shortened very economically. Nothing else need be changed to narrow or widen the entire awning, since the end panels would be identical in all cases. As to the assembly of the canopy, it is a simple expedient to more or less overlap the canopy slats 29. With reference to Figs. 4 and 5 it will be seen that in the illustrated showing the flanges of adjacent slats are spaced apart as indicated at 40 alternately with the flanges of adjacent slats being in contact with each other as indicated at 41. It will be seen that it would be a simple expedient to narrow the illustrated canopy by providing a space at 41 instead of permitting the slat flanges to contact. On the other hand, it would be a simple expedient to widen the canopy by providing contact or approximate contact where the spaces 40 now occur. It makes little difference how large the spaces 40 may be or how narrow, depending upon the desired width of canopy. However, it is preferable to always have some space between adjacent flanges at some parts of the canopy so that the canopy is adequately ventilated, the air following the tortuous path defined by the spaced flanges on the slats.

But in any event, it will be noted that the battens for the canopy and the water shed may be made in mass production in a considerable variety of lengths, and the assemblage of the canopy is the same for every length so that it would not add materially to the cost of manufacture even to fill a special order of only a few awnings in an irregular size.

My novel method of making the instant awning is believed to be sufficiently apparent from the foregoing as to warrant no further description herein.

It will be understood that modifications and variations may be effected without departing from the scope of the novel concepts of the present invention.

I claim as my invention:

1. In an awning, a pair of spaced end panels having aligned upper edges in an inclined plane, and a top structure secured to said end panels and comprising: a plurality of slats disposed generally in said inclined plane and extending in generally parallel relation to said upper edges, the upper surface of each slat being inclined with respect to said inclined plane with one side edge of each slat being higher than the other side edge thereof, and said slats being overlapped with the lower side edge portions of certain ones of said slats underlying the upper side edge portions of adjacent slats, and upstanding flanges on the lower side edges of said certain ones of said slats for providing channels for flow of water to the lower end of said top structure.

2. In an awning, a pair of spaced end panels having aligned upper edges in an inclined plane, and a top structure secured to said end panels and comprising: a plurality of slats disposed generally in said inclined plane and extending in generally parallel relation to said upper edges, the upper surface of each slat being inclined with respect to said inclined plane with one side edge of each slat being higher than the other side edge thereof, and said slats being overlapped with the lower side edge portions of certain ones of said slats underlying the upper side edge portions of adjacent slats, and upstanding flanges on the lower side edges of said certain ones of said slats for providing channels for flow of water to the lower end of said top structure, the upper surfaces of the slats on each side of a vertical plane midway between said end panels

10
15

being inclined toward the end panel on the same side of said plane.

3. In an awning, a pair of spaced end panels having inclined upper edges, a plurality of spaced generally parallel horizontal battens secured between said inclined upper edges of said end panels, inclined slat holding brackets on said battens, said brackets being oppositely inclined on opposite sides of a vertical plane midway between said end panels, and a plurality of slats secured to said brackets in generally parallel relation to said inclined upper edges of said end panels, the position of said slats on said brackets being adjustable in manufacture of said awning to adjust the width of the awning while maintaining symmetrical construction thereof.
